LIQUID JETTING APPARATUS AND LIQUID JETTING SYSTEM

CROSS REFERENCE TO RELATED APPLICATION

The present application claims priority from Japanese Patent Application No. 2018-068402 filed on Mar. 30, 2018, the disclosures of which is incorporated herein by reference in its entirety.

BACKGROUND

Field of the Invention

The present invention relates to a liquid jetting apparatus and a liquid jetting system which jet liquid from nozzles.

Description of the Related Art

As disclosed in Japanese Patent Application Laid-open No. 2011-245795, for example, there is known a liquid jetting apparatus including two piezo elements arranged to correspond to one nozzle and configured to circulate ink in the vicinity of the nozzle.

SUMMARY

However, in the liquid jetting apparatus having the above configuration, if some air bubbles are mixed into the liquid in an individual channel such as a pressure chamber and the like, then imbalance may occur in the pressure applied to the liquid by the two piezo elements to cause an unstable operation of jetting the liquid from the nozzle.

An object of the present teaching is to prevent unstable operation of jetting liquid from a nozzle due to some air bubbles mixed into the liquid, in a liquid jetting apparatus including two pressure chambers.

According to an aspect of the present teaching, there is provided a liquid jetting apparatus including: a nozzle plate having a nozzle; and a channel unit joined with the nozzle plate, wherein the channel unit is formed with: a first pressure chamber; a second pressure chamber; and a link channel linking the first pressure chamber and the second pressure chamber, and wherein in the channel unit, a dent portion is formed on an inner wall, which defines the link channel, at a part overlapping with an axis line of the nozzle, the dent portion being dented in a direction away from the nozzle.

According to the above configuration, if some air bubbles are mixed into fluid flowing through the link channel, it is possible to detain the air bubbles in the dent portion. The dent portion is formed in the part overlapping with the axis line of the nozzle and, in the part overlapping with the axis line of the nozzle, a balance is maintained for the pressure applied to the liquid in the first pressure chamber and the second pressure chamber. By detaining the air bubbles in the dent portion overlapping with the axis line of the nozzle, it is possible to prevent unstable operation of jetting the liquid from the nozzle due to the air bubbles mixed in the liquid.

Further, the air bubbles detained in the dent portion can be discharged from the dent portion by pressurizing and meanwhile circulating the liquid, for example, when the liquid is not jetted from the nozzle. By virtue of this, it is possible to preferably remove the air bubbles mixed in the liquid from the periphery of the nozzle before carrying out the operation of jetting the liquid from the nozzle. Further, because the air

2

bubbles need not be removed when the liquid is jetted from the nozzle, it is possible to prevent an increase in the load on the apparatus for removing the air bubbles.

According to the present teaching, it is possible to prevent 5 unstable operation of jetting liquid from the nozzle due to some air bubbles mixed into the liquid in a liquid jetting apparatus including two pressure chambers.

BRIEF DESCRIPTION OF THE DRAWINGS

10 FIG. 1 is a schematic configuration diagram of a printer according to a first embodiment of the present teaching.

FIG. 2 is a plan view of an ink jet head in FIG. 1.

15 FIG. 3 is an enlarged view of a part enclosed with a chain line in FIG. 2.

FIG. 4 is a cross-sectional view of FIG. 3 along the line IV-IV.

FIG. 5 is an enlarged view of FIG. 4.

20 FIG. 6 is an enlarged cross-sectional view of an ink jet head according to a modified example of the first embodiment.

FIG. 7 is a cross-sectional view of an ink jet head according to a second embodiment of the present teaching.

25 DESCRIPTION OF THE EMBODIMENTS

Hereinbelow, referring to the accompanying drawings, respective embodiments of the present teaching will be explained.

30 30 First Embodiment

<Overall Configuration of a Printer>

35 A printer 1 is an example of liquid jetting systems. As depicted in FIG. 1, the printer 1 includes a carriage 2, an ink jet head 3, a platen 4, conveyance rollers 5 and 6, a pressurizing tank 11, a negative pressure tank 12, air pumps P1 and P2, an ink pump P3, a tank 14, and a controller 15.

The carriage 2 is supported by two guide rails 7 and 8 40 extending in a scanning direction to move reciprocatingly together with the ink jet head 3 along the guide rails 7 and 8 in the predetermined scanning direction. Hereinbelow, the right side of the page of FIG. 1 is defined as the right side of the scanning direction whereas the left side of the page is defined as the left side of the scanning direction.

45 The ink jet head 3 is an example of liquid jetting apparatuses, and is mounted on the carriage 2. The ink jet head 3 is, as will be described later on, provided with 72 nozzles 201 to jet an ink as an example of liquids (see FIG. 2), four supply ports 3a, and three discharge ports 3b. Note that in FIG. 1, for convenience in illustration, only one supply port 3a and one supply port 3b are depicted.

50 The supply ports 3a are connected with ends of a pipe 9 at one side, while the discharge ports 3b are connected with 55 ends of the pipe 9 at the other side. The pipe 9 is connected midway with the pressurizing tank 11, the negative pressure tank 12, and the ink pump P3. The pressurizing tank 11 retains the ink. The pressurizing tank 11 is connected with the air pump P2 pressurizing the ink with air, and the supply tank 14 supplying the ink to the pressurizing tank 11. The pressurizing tank 11 is connected to such a part of the pipe 9 as close to the supply ports 3a. With the air pump P2 raising the pressure of the air in the pressurizing tank 11, the ink in the pressurizing tank 11 is pressurized to supply the pipe 9 with the ink retained in the pressurizing tank 11.

60 65 The negative pressure tank 12 also retains the ink. The negative pressure tank 12 is connected with the air pump P1

depressurizing the ink with air. The negative pressure tank 12 is connected to such a part of the pipe 9 as close to the discharge ports 3b. With the air pump P1 lowering the pressure of the air in the negative pressure tank 12, part of the ink flowing through the pipe 9 is sucked up into the negative pressure tank 12.

The ink pump P3 is arranged at the pipe 9 between the tanks 11 and 12. The ink pump P3 supplies the ink to the pressurizing tank 11 from the negative pressure tank 12. In the printer 1, along with the driving of the pumps P1 to P3, the ink circulates inside the respective parts of the pipe 9 and ink jet head 3. Each of the pumps P1 to P3 causes the ink to flow in the pressure chambers 211a and the pressure chambers 211b of an aforementioned channel unit 21.

The platen 4 is arranged to face the nozzles 201 of the ink jet head 3, and to extend in the scanning direction and in a conveyance direction orthogonal to the scanning direction. A recording sheet M is placed on the platen 4. The conveyance rollers 5 and 6 convey the recording sheet M along the conveyance direction. The conveyance roller 5 is arranged on the upstream side from the carriage 2 in the conveyance direction while the conveyance roller 6 is arranged on the downstream side from the carriage 2 in the conveyance direction.

The controller 15 controls the carriage 2, the pumps P1 to P3, the conveyance rollers 5 and 6, and piezoelectric elements 22c (see FIG. 4), respectively,

In the printer 1, due to the control by the controller 15, each time the recording sheet M is conveyed by the conveyance rollers 5 and 6 in the conveyance direction through a predetermined distance, the carriage 2 is moved in the scanning direction while the ink is jetted from the 72 nozzles 201 of the ink jet head 3. By virtue of this, printing is carried out on the recording sheet M.

<Ink Jet Head>

As depicted in FIGS. 2 to 5, the ink jet head 3 has a nozzle plate 20, a channel unit 21, and the piezoelectric elements 22c. Note that in FIGS. 4 and 5, a direction perpendicular to the page of the drawings corresponds to the second direction.

The nozzle plate 20 has the nozzles 201. The nozzle plate 20 in this embodiment is formed therein with the 72 nozzles 201 penetrating therethrough in the plate-thickness direction. In the nozzle plate 20, six nozzle rows are arranged in predetermined positions at intervals in the scanning direction. Each of the nozzle rows includes 12 nozzles 201. Further, the 12 nozzles 201 of each nozzle row are aligned in the conveyance direction at predetermined intervals.

<Channel Unit>

A channel unit 21 has the surface S1 against the nozzle plate 20. The surface S1 is attached to the nozzle plate 20. The channel unit 21 is formed with the pressure chambers 211a, pressure chambers 211b, throttle channels 212a, throttle channels 212b, descender channels 213a, descender channels 213b, and channels 214, each set of which has 72 members. Further, the channel unit has 4 manifolds 215a, 3 manifolds 215b, 4 damper chambers 216a, and 3 damper chambers 216a.

The pressure chambers 211a and the pressure chambers 211b are linked through the descender channels 213a, the channels 214, and the descender channels 213b. The channels 214 connect the descender channels 213a and the descender channels 213b. In this embodiment, link channels 260 refer to the channels formed from the descender channels 213a, the channels 214, and the descender channels 213b. That is, the channel unit 21 is formed therein with the link channels 260.

As depicted in FIG. 4, the channel unit 21 is constructed from a stacked body where seven plates 31 to 37 are stacked in layers along a direction perpendicular to the surface S1. The plates 31 to 37 are stacked in the numbering order in the orientation approaching the platen 4 along the direction perpendicular to the surface S1. The seven plates 31 to 37 in the stacked body are attached to each other with a thermo-setting adhesive.

The plate 37 has the surface S1 against the nozzle plate 20, and the surface S3 against the plate 36. The plate 37 has through holes 270 formed therethrough in the plate-thickness direction to construct the channels 214. Openings 271 of the through holes 270 at the side of the nozzle plate 20 are covered by the nozzle plate 20. That is, the openings 271 define the contours of end portions of the channels 214 at the side of the nozzle plate 20.

The ink jet head 3 has the same number 72 of link channels 260 as that of nozzles 201. That is, the surface S1 of the plate 37 defines the same number 72 of openings 271 as that of nozzles 201.

The plate 36 has the surface S2 against the plate 37. The surface S2 is joined with the plate 37. The plate 36 is formed with the openings 36a and the openings 36b, each set of which has 72 members. The openings 36a serve as the boundaries between the descender channels 213a, and the channels 214 extending in a direction parallel to the surface S1. The openings 36b serve as the boundaries between the descender channels 213b and the channels 214.

The surface S2 defines the same number 72 of openings 36a as that of nozzles 201 and the same number 72 of openings 36b as that of nozzles 201. The openings 36a are at the surface S2 of the descender channels 213a while the openings 36b are at the surface S2 of the descender channels 213b. Further, the plate 36 has a plate portion 21e. The plate portion 21e is arranged between the openings 36a and the openings 36b in a first direction parallel to the surface S1.

As depicted in FIGS. 2 to 4, the plate 31 is formed with the pressure chambers 211a and the pressure chambers 211b, each set of which has 72 members. The pressure chambers 211a and 211b are shaped with the scanning direction and the first direction respectively as their longitudinal directions. As viewed from a direction perpendicular to the surface S1, the pressure chambers 211a and 211b are shaped in rectangles. The pressure chambers 211a and 211b extend along a plane parallel to the scanning direction and the conveyance direction, respectively.

The 72 pressure chambers 211a form 6 pressure chamber rows Qa. Each of the pressure chamber rows Qa includes 12 pressure chambers 211a. Further, the 72 pressure chambers 211b form 6 pressure chamber rows Qb. Each of the pressure chamber rows Qb includes 12 pressure chambers 211b. The 12 pressure chambers 211a belonging to each pressure chamber row Qa are arranged in the conveyance direction at a predetermined distance from each other. The 12 pressure chambers 211b belonging to each pressure chamber row Qb are arranged in the conveyance direction at a predetermined distance from each other.

The 6 pressure chamber rows Qa and the 6 pressure chamber rows Qb are arranged in the scanning direction. In particular, the 6 pressure chamber rows Qa and the 6 pressure chamber rows Qb are arranged, from left to right in the scanning direction, in the order of Qa, Qb, Qb, Qa, Qa, Qb, Qb, Qa, Qa, Qb, Qb, and Qa.

That is, except the two pressure chamber rows Qa at the left and right ends in the scanning direction, the pressure chamber rows Qa and the pressure chamber rows Qb are arranged in pairs successively in the scanning direction. In

the adjacent pressure chamber rows Qa and pressure chamber rows Qb in the scanning direction, the pressure chambers 211a and 211b are shined from each other at a pitch in the conveyance direction.

The plates 32 to 36 define the four manifolds 215a and the three manifolds 215b. Each of the manifolds 215a extends in the conveyance direction, and one end thereof in the conveyance direction is connected to the supply port 3a. Further, each of the manifolds 215b also extends in the conveyance direction, and one end thereof along the conveyance direction is connected to the supply port 3b.

The four manifolds 215a and the three manifolds 215b are arranged in the scanning direction. In particular, the four manifolds 215a and the three manifolds 215b are arranged, from left to right along the scanning direction, in the order of 215a, 215b, 215a, 215b, 215a, 215b, and 215a.

The pressure chambers 211a are connected with the manifolds 215a through the throttle channels 212a. Further, the pressure chambers 211b are connected with the manifolds 215b through the throttle channels 212b. The pressure chamber 211a and the pressure chamber 211b are arranged along the first direction parallel to the surface S1. For example, each of the pressure chambers 211a and 211b has a certain cross-sectional area perpendicular to the first direction. Further, the cross-sectional areas of the pressure chambers 211a and 211b are identical.

As depicted in FIG. 4, each of the throttle channels 212a is formed to cross over a boundary between the plates 32 and 33. Further, the throttle channels 212b are also formed to cross over a boundary between the plates 32 and 33. The throttle channels 212a are provided individually for the pressure chambers 211a. Further, the throttle channels 212b are provided for the pressure chambers 211b.

The throttle channels 212a provided for the pressure chambers 211a forming the first pressure chamber row Qa from the left of the page of FIG. 2 respectively connect the left ends of the pressure chambers 211a forming the pressure chamber row Qa and the manifold 215a adjacent to the left side of the pressure chamber row Qa. Much the same is true as the first pressure chamber row Qa on the third pressure chamber row Qb, the fifth pressure chamber row Qa, the seventh pressure chamber row Qb, the ninth pressure chamber row Qa, and the eleventh pressure chamber row Qb, from the left of the page of FIG. 2. The throttle channels 212b provided for the pressure chambers 211b forming the second pressure chamber row Qb from the left of the page of FIG. 2 respectively connect the right ends of the pressure chambers 211b forming the pressure chamber row Qb and the manifold 215b adjacent to the right side of the pressure chamber row Qb. Much the same is true as the second pressure chamber row Qb on the fourth pressure chamber row Qa, the sixth pressure chamber row Qb, the eighth pressure chamber row Qa, the tenth pressure chamber row Qb, and the twelfth pressure chamber row Qa, from the left of the page of FIG. 2.

The descender channels 213a and 213b extend in a direction perpendicular to the surface S1. The respective descender channels 213a are formed of through holes formed in the respective plates 32 to 37 to overlap with each other in the direction perpendicular to the surface S1. The respective descender channels 213b are also formed of through holes formed in the respective plates 32 to 37 to overlap with each other in the direction perpendicular to the surface S1. The descender channels 213a are provided for the pressure chambers 211a. Further, the descender channels 213b are provided for the pressure chambers 211b.

The surface S3 of the plate 37 is formed with 72 openings 272. Each of the 72 openings 272 is in communication with one opening 36a formed in the plate 36 and one opening 36b formed in the plate 36. The surface S3 defines the openings 272. The openings 272 are openings of the through holes 270 formed in the plate 37 at the side of the plate 36. If a second direction is defined as orthogonal to the first direction and parallel to the surface S1, then the respective openings 272 are sized larger along the first direction than along the second direction.

The descender channels 213a provided for the pressure chambers 211a forming the first pressure chamber row Qa from the left of the page of FIG. 2 respectively connect the right ends of the pressure chambers 211a forming the pressure chamber row Qa and the corresponding channels 214 through the openings 36a and the openings 272. Much the same is true as the first pressure chamber row Qa on the third pressure chamber row Qb, the fifth pressure chamber row Qa, the seventh pressure chamber row Qb, the ninth pressure chamber row Qa, and the eleventh pressure chamber row Qb, from the left of the page of FIG. 2. The descender channels 213b provided for the pressure chambers 211b forming the second pressure chamber rows Qb from the left of the page of FIG. 2 respectively connect the left ends of the pressure chambers 211b forming the pressure chamber row and the corresponding channels 214 through the openings 36b and the openings 272. Much the same is true as the second pressure chamber row Qb on the fourth pressure chamber row Qa, the sixth pressure chamber row Qb, the eighth pressure chamber row Qa, the tenth pressure chamber row Qb, and the twelfth pressure chamber row Qa, from the left of the page of FIG. 2.

As depicted in FIGS. 4 and 5, the channels 214 extend in the first direction to link the pressure chambers 211a and the pressure chambers 211b. In this embodiment, as viewed from the direction perpendicular to the surface S1, the channels 214 have a constant width from the position for the openings 36a to have the maximum diameter to the position for the openings 36b to have the maximum diameter.

Here, the channel unit 21 has a dent portion 21c formed in an inner wall defining the link channel 260 (the inner wall defining each channel 214 as one example). The dent portion 21c is formed in such a part as on an axis line L of the nozzle 201 to be dented in a direction away from the nozzle 201. In this embodiment, the dent portion 21c is dented to have a rectangle shape on a cross section orthogonal to the second direction.

The dent portion 21c is formed in a central portion of the channel 214 in the longitudinal direction (in other words, in the communication portion 21d in communication with the nozzle 201), by way of etching part of the surface of the plate 36. That is, the channel unit 21 has the plate 36 whose surface is formed with the dent portion 21c by way of partial etching.

The dent portion 21c has such a depth in the plate-thickness direction of the plate 36 (to be simply referred to below as "depth") as smaller than the plate-thickness of the plate 36. In other words, the dent portion 21c is formed without penetrating through the plate 36. It is possible to set an appropriate depth for the dent portion 21c and, for example, the dent portion 21c is set to a value of being not larger than 1/2 of the plate thickness of the plate 36. The dent portion 21c is exposed to the inside of the channel 214.

The dent portion 21c has such a length in the first direction as smaller than the length of the channel 214 in the first direction. It is possible to set an appropriate length for the dent portion 21c in the first direction and, for example,

the dent portion 21c is set to a value of being not larger than $\frac{1}{2}$ of the length of the channel 214 in the first direction.

Further, in the first embodiment, as viewed from the axial direction of the nozzle 201, the maximum size of the dent portion 21c in the first direction is smaller than the inner diameter of the nozzle 201 at the upstream end in the jetting direction of the nozzle 201. Further, as viewed from the axial direction of the nozzle 201, the maximum size of the dent portion 21c is set to a value of being not larger than 70 μm in the first direction.

The dent portion 21c contains some air bubbles mixed in the ink flowing through the channel 214. With the dent portion 21c being set to the above value of the length in the first direction, the channel unit 21 contains air bubbles sized comparatively small. The dent portion 21c removes, from the ink, the air bubbles being smaller than a certain size mixed in the ink flowing through the channel 214.

The air bubbles contained in the dent portion 21c are discharged from the dent portion 21c by way of the controller 15 controlling at least one of the pumps P1 to P3 while pressurizing the ink inside the channel 214 to cause the same to flow therethrough. Because the dent portion 21c is sized very small in the first direction, the air bubbles contained in the dent portion 21c can be discharged from the dent portion 21c by driving the pumps P1 to P3 over a comparatively short time.

Further, as viewed from the direction perpendicular to the surface S1, the openings 36a and the openings 36b lie within the projections of the channels 214, respectively. Further, as viewed from the direction perpendicular to the surface S1, the maximum diameter of the openings 36a and the maximum diameter of the openings 36b are smaller than the width of the channels 214.

As depicted in FIGS. 2 to 4, the manifolds 215a and 215b are formed by overlapping, along the direction perpendicular to the surface S1, the through holes penetrating through the plates 34 and 35, with recesses 218a and recesses 218b formed in the surface of the plate 36 against the plate 35.

The four manifolds 215a are arranged at intervals in the scanning direction. Each of the four manifolds 215a extends in the conveyance direction. Further, the three manifolds 215b are also arranged at intervals in the scanning direction. Each of the three manifolds 215b also extends in the conveyance direction and arranged between two adjacent manifolds 215a in the scanning direction.

Due to the drives of the pumps P1 to P3, the ink flowing through the pipe 9 to supply the ink jet head 3 from the supply ports 3a is further supplied to the manifolds 215a. The ink supplied to the manifolds 215a from the supply ports 3a is further supplied to the throttle channels 212a and 212b.

Then, the ink is supplied to the manifolds 215b after flowing through and in the order of one of each pair of the throttle channels 212a and 212b, one of each pair of the descender channels 213a and 213b, the other of each pair of the descender channels 213a and 213b, and the other of each pair of the throttle channels 212a and 212b.

Further, due to the drives of the pumps P1 to P3, the ink supplied to the manifolds 215b is discharged to the pipe 9 from the supply ports 3b. The ink discharged from the supply ports 3b is returned to the negative pressure tank 12 through the pipe 9. By virtue of this, in this embodiment, the ink is circulated between the ink jet head 3 and the tanks 11 and 12.

The damper chambers 216a and 216b are formed in the plate 37. The damper chambers 216a are formed in positions overlapping with the manifolds 215a along the direction

perpendicular to the surface S1, while the damper chambers 216b are formed in positions overlapping with the manifolds 215b along the direction perpendicular to the surface S1.

The damper chambers 216a are distanced from the manifolds 215a by partition walls 217a formed in the plate 36. The damper chambers 216b are distanced from the manifolds 215b by partition walls 217b formed in the plate 36. The damper chambers 216a and 216b allow the partition walls 217a and 217b to deform in the direction perpendicular to the surface S1. Due to the deformation of the partition walls 217a and 217b, the ink inside the manifolds 215a and 215b is restrained respectively from pressure variation.

<The Piezoelectric Elements>

The piezoelectric elements 22c apply a pressure to the ink flowing through the pressure chambers 211a and 211b to jet the ink from the nozzles 201. In the ink jet head 3, the 144 piezoelectric elements 22c are provided to correspond respectively to the 144 pressure chambers 211a and 211b.

As depicted in FIGS. 2 to 4, an actuator 22 is provided on the surface of the channel unit 21 on a side opposite to the nozzle plate 20. The actuator 22 is constructed from two piezoelectric layers 25 and 26, a common electrode 27, 144 individual electrodes 28, and a vibration plate, and has the 144 piezoelectric elements 22c. The piezoelectric layers 25 and 26 are formed of a piezoelectric material. For example, a piezoelectric material whose main component is lead zirconate titanate (PZT) may be used.

The piezoelectric layer 25 is arranged to superimpose the plate 31 of the channel unit 21 while the piezoelectric layer 26 is arranged to superimpose the piezoelectric layer 25. The piezoelectric layer 25 may be formed of a different material from the piezoelectric layer 26. In such a case, the piezoelectric layer 25 may be formed of, for example, an insulating material other than piezoelectric materials such as a synthetic resin material or the like.

The common electrode 27 is arranged between the piezoelectric layer 25 and the piezoelectric layer 26 to extend continuously throughout almost the entire area of the piezoelectric layers 25 and 26. The common electrode 27 is kept at the ground potential. The 144 individual electrodes 28 are provided individually for the total of 144 pressure chambers 211a and 211b.

As viewed from the direction perpendicular to the surface S1, the respective individual electrodes 28 have an approximately rectangular planar shape elongated in the scanning direction. The respective individual electrodes 28 are arranged to overlap with central positions of the corresponding pressure chambers 211a or 211b along an up/down direction. End portions of the respective individual electrodes 28 at the other side than the descender channels 213a or 213b along the scanning direction extend up to positions not overlapping with the pressure chambers 211a or 211b, and their leading ends serve as connecting terminals 28c for connection with a wiring member.

The connecting terminals 28c of the 144 individual electrodes 28 are connected to a predetermined driver IC via the wiring member. The 144 individual electrodes 28 are set individually by the driver IC to either the ground potential or a predetermined drive potential (for example, 20 V or so). Further, by arranging the common electrode 27 and the 144 individual electrodes 28 in the above manner, such parts of the piezoelectric layer 26 as interposed between the individual electrodes 28 and the common electrode 27 function as active portions polarized in the direction perpendicular to the surface S1. Each of the piezoelectric elements 22c has an active portion polarized in the direction perpendicular to the surface S1.

In the piezoelectric elements 22c, all of the individual electrodes 28 are kept at the same ground potential as the common electrode 27 when the ink is not jetted from the nozzles 201 (in the standby state). Further, in the piezoelectric elements 22c, when the ink is jetted from a particular nozzle 201, the potential is switched to the predetermined drive potential applied to the two individual electrodes 28 corresponding to the pressure chamber 211a and the pressure chamber 211b connected to that particular nozzle 201.

Thereafter, such an electrical field arises as parallel to the polarization direction of the two piezoelectric elements 22c corresponding to the above two individual electrodes 28, such that the above two piezoelectric elements 22c contract in a horizontal direction orthogonal to the polarization direction of the above two piezoelectric elements 22c. By virtue of this, in the two piezoelectric elements 22c, such parts of the piezoelectric layers 25 and 26 as overlapping with the respective pressure chambers 211a and 211b along the up/down direction deform to project as a whole toward the pressure chambers 211a and 211b.

As a result, the volumes of the pressure chambers 211a and 211b decrease such that the ink pressure in the pressure chambers 211a and 211b increases, thereby jetting the ink from the particular nozzle 201. After the ink is jetted, the potential of the above two individual electrodes 28 returns to the ground potential. By virtue of this, the piezoelectric layers 25 and 26 are restored to the state before the deformation.

Here, in the first embodiment, the controller 15 causes the piezoelectric elements 22c, which correspond to the nozzles 201 not jetting the ink among the 72 nozzles 201, to deform in a backward move from the pressure chambers 211a and 211b corresponding to those nozzles 201. That is, the parts of the piezoelectric layers 25 and 26 overlapping with the respective pressure chambers 211a and 211b in the up/down direction deform to project as a whole in a direction away from the pressure chambers 211a and 211b.

When driving the printer 1, among the 72 nozzles 201 formed in the nozzle plate 20, it is possible to carry out printing on the recording sheet M by jetting the ink only from specified nozzles 201. In such cases, the 72 nozzles 201 include those jetting the ink and those not jetting the ink. By way of such backward deformation of the piezoelectric elements 22c corresponding to the nozzles 201 not jetting the ink as from the pressure chambers 211a and 211b corresponding to those nozzles 201, the ink is restrained from being jetted from the nozzles 201 not being scheduled to jet the ink.

As explained above, according to the ink jet head 3, if air bubbles are mixed into a fluid flowing through the channel 214, it is possible to detain the air bubbles in the dent portion 21c. Because the dent portion 21c is formed in the part overlapping with the axis line L of the nozzle 201, a balance is maintained for the pressure applied to the ink in the pressure chamber 211a and the pressure chamber 211b. By detaining the air bubbles in the dent portion 21c, it is possible to prevent unstable operation of jetting the ink from the nozzle 201 due to the air bubbles mixed in the circulating ink.

Further, the air bubbles detained in the dent portion 21c can be discharged from the dent portion 21c by pressurizing and circulating the ink when the ink is not jetted from the nozzle 201, for example. By virtue of this, it is possible to preferably eliminate the air bubbles mixed in the circulating ink from the periphery of the nozzle 201 before carrying out the operation of jetting the ink. Further, because the air bubbles need not be eliminated when the ink is jetted from

the nozzle 201, it is possible to prevent an increase in the load on the ink jet head 3 for eliminating the air bubbles.

Further, if comparatively large air bubbles are detained in the channel 214 so as not to fit in the dent portion 21c, then it is possible to cause impediment to a normal ink flow and adhesion of the ink. To address this problem, in the ink jet head 3, such comparatively large air bubbles are eliminated from the channel 214 along with the ink flow independently from the dent portion 21c. Therefore, it is possible to prevent such problem from occurring.

Further, on the cross section orthogonal to the second direction, because the dent portion 21c is dented to have the shape of a rectangle, it is easy to detain the air bubbles mixed in the ink flowing through the channel 214 in the first direction, in a corner portion inside the dent portion 21c. Hence, it is possible to efficiently detain the air bubbles in the dent portion 21c.

Further, as viewed from the axial direction of the nozzle 201, the maximum size of the dent portion 21c along the first direction is smaller than the inner diameter of the nozzle 201 at the upstream end along the jetting direction. Therefore, it is possible to preferably detain the comparatively small air bubbles in the dent portion 21c.

Further, as viewed from the axial direction of the nozzle 201, the maximum size of the dent portion 21c along the first direction is set to a value not larger than 70 μm . Therefore, it is possible to preferably detain the air bubbles sized not larger than 70 μm in the dent portion 21c.

Further, the channel unit 21 has the plate 36, and the dent portion 21c is formed in the surface of the plate 36 by way of the partial etching. It is possible to arrange the dent portion 21c easily inside the channel 214 by using such kind of plate 36.

The channel unit 21 is formed with the manifold 215a connected to the pressure chamber 211a and the manifold 215b connected to the pressure chamber 211b. Further, while the plate 36 is provided with the dent portion 21c, the recess 218a and the recess 218b are provided respectively in the part facing the manifolds 215a and 215b.

In this manner, if one plate 36 is provided with the dent portion 21c and the recesses 218a and 218b, then for example, by processing a plurality of areas of the plate 36, it is possible to efficiently form the dent portion 21c and the recess 218a and 218b.

Further, the dent portion 21c and the recesses 218a and 218b may be formed simultaneously by way of the partial etching of the plurality of areas in the plate 36. Therefore, through the one etching process, it is possible to efficiently form the dent portion 21c and the recesses 218a and 218b.

Note that the recesses 218a and 218b may be provided in the same surface as that provided with the dent portion 21c of the plate 36. With that, through an etching process of the same surface of the plate 36, it is possible to efficiently form the dent portion 21c and the recesses 218a and 218b at one time.

Further, the controller 15 causes the piezoelectric elements 22c, which correspond to the nozzles 201 not jetting the ink among the 72 nozzles 201, to deform in the backward move from the pressure chambers 211a and 211b corresponding to those nozzles 201. Therefore, when the controller 15 drives the pumps P1 to P3 to eliminate the air bubbles from the dent portion 21c, it is possible to prevent the ink from being mistakenly jetted from the nozzles 201 which are not scheduled to jet the ink.

In the above description, the surface S1 corresponds to the first surface, the manifold 215a corresponds to the first manifold, and the manifold 215b corresponds to the second

11

manifold. Further, the recess **218a** corresponds to the first recess, and the recess **218b** corresponds to the second recess. Further, the pressure chambers **211a** correspond to the first pressure chamber, and the pressure chambers **211b** correspond to the second pressure chamber.

Modified Embodiments

Hereinbelow, explanation will be made on a few modified embodiments and other embodiments, focusing on the difference from the first embodiment. As depicted in FIG. 6, in a plate **136** of an ink jet head **103**, in a cross section orthogonal to the second direction, a dent portion **121c** is dented to have a wedge shape tapering in a direction away from the nozzle **201**. In other words, as viewed from the second direction, the dent portion **121c** is dented to assume a triangle whose one vertex is located at a communication portion **121d**. In the ink jet head **103** having such kind of the dent portion **121c**, the same effect is also exerted as the ink jet head **3**.

Further, the dent portion **121c** has a symmetrical shape with respect to the nozzle axis direction of the nozzle **201** on the cross section orthogonal to the second direction. However, it may have a nonsymmetrical shape.

For example, as viewed on the cross section orthogonal to the second direction, the inclination angle $\theta 1$ of the surface at the side of the openings **36a** to a surface **S1** may differ from the inclination angle $\theta 2$ of the surface at the side of the openings **36b** to the surface **S1**. In such a case, the angle $\theta 2$ may be larger than the $\theta 1$. For example, the angle $\theta 2$ may have a value two times the angle $\theta 1$ or more or a value three times the angle $\theta 1$.

Second Embodiment

As depicted in FIG. 7, a thin portion **236c** may be formed in a plate **236** being closest to a channel **2214** among the seven plates of the channel unit. The thin portion **236c** is formed in a part of the plate **236**, overlapping with the axis line **L** of the nozzle **201**. Further, a recess may be formed to construct an airtight chamber **238** in such a position of the plate **236** on a side opposite to the channel **2214** with respect to the thin portion **236c**. The airtight chamber **238** is provided in contact with the thin portion **236c**. In the ink jet head **203**, with the thin portion **236c** dented toward the airtight chamber **238**, a dent portion **221c** is provided in the plate **236** being closest to the channel **2214**.

In particular, the thin portion **236c** is formed by partially etching the surface of the plate **236** at the other side than the channel **2214**. Further, the airtight chamber **238** is provided to overlap with the thin portion **236c** between the plate **236**, and the plate **35** adjacent to the plate **236**.

Here, the seven plates of the stacked body of the channel unit are, as described earlier on, attached to each other with a thermosetting adhesive. By virtue of this, along with the cooling after heating adhesion of the seven plates, the inner pressure of the airtight chamber **238** is lower than that of the channel **2214**. As a result, the ink jet head **203** is formed with the dent portion **221c**.

In the second embodiment, the controller **15** drives the pumps **P1** to **P3** to change the fluid pressure inside the channel **2214**, so as to deform the thin portion **236c** in the stacking direction of the seven plates (the direction perpendicular to the surface **S1**).

In particular, the controller **15** drives the pumps **P1** to **P3** to pressurize the ink flowing through the channel **2214**, so as to raise the fluid pressure inside the channel **2214** to be

12

higher than the inner pressure of the airtight chamber **238**. By virtue of this, the thin portion **236c** is dented toward the airtight chamber **238** to form the dent portion **221c**.

Further, the controller **15** drives the pumps **P1** to **P3** to make the fluid pressure of the channel **2214** to be lower than the inner pressure of the airtight chamber **238**, thereby reducing the depth of the dent portion **221c**. By virtue of this, the air bubbles detained in the dent portion **221c** are discharged from the dent portion **221c**. in this manner, in the ink jet head **203** having the dent portion **221c** of such kind, the same effect is also exerted as the ink jet head **3**.

The present teaching is not limited to the above embodiments but, without departing from the true scope and the spirit of the present teaching, its configuration may be changed, supplemented, and/or deleted.

In the above manner, the present teaching has an excellent effect in enabling prevention of unstable operation of jetting a liquid from the nozzles due to the air bubbles mixed in the liquid, in a liquid jetting apparatus including two pressure chambers. Therefore, it is beneficial to widely apply the present teaching to liquid jetting apparatuses capable of fulfilling the significance of the effect.

What is claimed is:

1. A liquid jetting apparatus comprising:
a nozzle plate having a nozzle; and
a channel unit joined with the nozzle plate,
wherein the channel unit is formed with: a first pressure chamber; a second pressure chamber; and a link channel linking the first pressure chamber and the second pressure chamber, and

wherein in the channel unit, a dent portion is formed on an inner wall, which defines the link channel, at a part overlapping with an axis line of the nozzle, the dent portion being dented in a direction away from the nozzle, and

wherein the dent portion and the inner wall of the link channel form a first edge and a second edge, the dent portion being interposed between the first edge and the second edge.

2. The liquid jetting apparatus according to claim 1,
wherein the channel unit has a first surface facing the nozzle plate,
wherein the first pressure chamber and the second pressure chamber are arranged in a first direction parallel to the first surface, and

wherein as viewed from a second direction which is parallel to the first surface and orthogonal to the first direction, the dent portion has a cross section orthogonal to the second direction dented in a rectangle shape.

3. The liquid jetting apparatus according to claim 1,
wherein the channel unit has a first surface facing the nozzle plate,

wherein the first pressure chamber and the second pressure chamber are arranged in a first direction parallel to the first surface, and

wherein as viewed from a second direction which is parallel to the first surface and orthogonal to the first direction, the dent portion has a cross section orthogonal to the second direction dented in a wedge shape tapering in a direction away from the nozzle.

4. The liquid jetting apparatus according to claim 1,
wherein the channel unit has a first surface facing the nozzle plate, and

wherein as viewed from a direction along the axis line of the nozzle, the maximum size of the dent portion in a first direction parallel to the first surface is smaller than

13

an inner diameter, of the nozzle, at an upstream end in a jetting direction in which liquid is jetted from the nozzle.

5. The liquid jetting apparatus according to claim 1, wherein the channel unit has a first surface facing the nozzle plate, and wherein as viewed from a direction along the axis line of the nozzle, the maximum size of the dent portion in a first direction parallel to the first surface is equal to or smaller than 70 μm .

6. The liquid jetting apparatus according to claim 1, further comprising:

15 piezoelectric elements provided to correspond respectively to the first pressure chamber and the second pressure chamber, the piezoelectric elements being configured to apply pressure to liquid flowing through the first pressure chamber and the second pressure chamber to jet the liquid from the nozzle; and a controller configured to control the piezoelectric elements,

20 wherein in a case where the liquid is not jetted from the nozzle, the controller is configured to cause the piezoelectric elements to deform to project in a direction away from the first pressure chamber and the second pressure chamber.

- 25 7. The liquid jetting apparatus according to claim 1, wherein the channel unit has a plate having a surface in which the dent portion is formed.

8. The liquid jetting apparatus according to claim 7, 30 wherein the channel unit is further formed with: a first manifold in communication with the first pressure chamber; and a second manifold in communication with the second pressure chamber, and wherein the plate having the dent portion is formed with: 35 a first recess defining the first manifold; and a second recess defining the second manifold.

14

9. The liquid jetting apparatus according to claim 1, wherein the channel unit has a first surface facing the nozzle plate,

wherein the channel unit is constructed of a stacked body in which plates are stacked in a direction perpendicular to the first surface,

wherein in a closest plate closest to the link channel among the plates, a thin portion is formed in a part positioned on the axis line of the nozzle, the thin portion being thinner in plate thickness than a periphery of the part,

an airtight chamber is defined by the thin portion on a side opposite to the link channel with respect to the thin portion, and

the dent portion is formed in the closest plate by the thin portion being dented toward the airtight chamber.

10. The liquid jetting apparatus according to claim 9, wherein the thin portion is formed by partially etching a surface, of the closest plate, on the side opposite to the link channel, and

wherein the airtight chamber is formed to overlap with the thin portion between the closest plate and an adjacent plate which is included in the plates and adjacent to the closest plate.

11. The liquid jetting apparatus according to claim 9, wherein the plates in the stacked body are attached to each other with a thermosetting adhesive.

12. A liquid jetting system comprising:
the liquid jetting apparatus as defined in claim 9;
a pump causing liquid to flow into the first pressure chamber and the second pressure chamber; and
a controller configured to control the pump,
wherein the controller is configured to drive the pump to change a fluid pressure inside the link channel and thereby deform the thin portion in a stacking direction of the plates.
